OVERSHOE

Lillian Hamalainen, Virginia, Minn.

Application January 4, 1938, Serial No. 183,349

1 Claim. (CL 36—7.3)

This invention relates to rubber overshoes, and its general object is to provide an overshoe of the storm type that can be readily applied and removed with respect to shoes, with minimum effort on the part of the user, yet snugly fits the shoe when in position thereon, so as to prevent slippage or casual removal.

A further object is to provide a rubber overshoe, that has its upper split or notched at the rear end thereof, to increase the size of the rear end, and thereby facilitate the application thereof to the shoe, but when applied to the shoe, the notched portion is drawn together to set up a snug engagement with the shoe.

Another object is to provide an overshoe that includes a ledge extending about the rear end of the upper, to act as an abutment for use in removing the overshoe.

A further object is to provide an overshoe of the character set forth, that is simple in construction, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompany drawing wherein like characters denote like or corresponding parts throughout the several views, and in which:

Figure 1 is a view of the rear portion of a rubber overshoe, constructed in accordance with my invention, with the closure flap in applied or fastened position.

Figure 2 is a sectional view taken approximately on line 2—2 of Figure 1, looking in the direction of the arrows.

Figure 3 is a perspective view of the rear portion of the overshoe, with the closure flap in open position.

Referring to the drawing in detail, it will be noted that I have illustrated an overshoe constructed in accordance with the present invention, that is, of the type generally worn by women, but it will be understood that my invention is applicable to any type of overshoe.

The rear portion of the upper of the overshoe, as shown, is indicated by the reference numeral 1, and is thickened to provide a lug 2 arranged centrally on the outside of the rear portion and extending downwardly from its upper edge, as best shown in Figure 3.

The thickened portion or lug 2 is provided with a V-shaped notch 3 that extends through the rear portion and opens through the upper end thereof, while the lower or apex end of the

notch 3 terminates adjacent to the lower end of the lug.

Formed on or otherwise secured to the upper and laterally of the lug, is one end of a closure flap 4, which is of a length to extend about the lug 2, and has its free end reduced, with socket fastener members 5 mounted thereon for cooperation with companion stud members 6 fixed to the upper in the path thereof, for securing the flap in position for use, as clearly shown in Figure 1. When so secured, the walls of the notch are drawn together, so that the rear portion 1 is disposed in snug association or fitting engagement with the shoe, when the overshoe is applied thereto. However, when the flap is arranged in the position of Figure 3, it will be obvious that the notch is completely open, so that the overshoe can be readily applied to the shoe.

In order to facilitate the removal of the overshoe, I provide an elongated projection 7 that is formed on and extends about the rear portion 1 below the lug 2. The projection 7 terminates in pointed ends that merge into the upper, and the upper surface of the projection provides a ledge or abutment means to receive the fingers of the user, in removing the overshoe, as will be apparent.

The lug 2 and projection 7 are preferably integrally connected to each other, so that the projection 7 acts to reinforce the lug and prevents tearing of the material below the notch 3, in the event of rough usage, in applying and removing the overshoe.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:

A rubber overshoe comprising an upper thickened to provide a substantially rectangular lug 45 formed exteriorly thereon centrally of the heel portion and extending vertically from the upper edge thereof, said lug and upper having a normally open V-shaped notch therein extending through said upper edge and having its apex 50 terminating adjacent to the lower end of the lug, a flap having one end formed on the outside of said heel position laterally of the lug and the inside of the heel portion being smooth and free from obstructions throughout the area 55 thereof about the notch, and means for detachably securing the flap to the upper and about said lug for completely covering the notch and for drawing the walls thereof toward each other.

LILLIAN HAMALAINEN. 60
